UNITED STATES PATENT OFFICE

2,357,031

INTERNAL-COMBUSTION ENGINE

Dwight W. Stabler, Venice, Calif.

Application March 7, 1942, Serial No. 433,741

1 Claim. (Cl. 123—51)

My invention has to do with internal combustion engines. In some of its more particular aspects, it relates to two cycle engines employing opposed pistons although of course my improvements are susceptible of use in other types of internal combustion engines.

Among the objects of my invention, I aim to provide an internal combustion engine having simple and effective means for adjustably controlling compression at the will of the operator. I am aware that various expedients have been attempted with the aim of accomplishing such control but, at least for the most part, those attempts have been impracticable in that the means employed were too complicated and inherently of a nature which would not withstand the stresses to which they would be subjected in actual operation. In general, I accomplish this object by eccentric means, which means may be manually or otherwise adjusted to control the inward travel of the pistons into the cylinders during the compression stroke.

Another object is to provide a novel and efficient means of efficiently scavenging the cylinders without requiring valve means other than the pistons themselves.

Another object is the fulcruming of the rock lever of an engine at a point closer to one end than to the other for obtaining improved results.

Another object involves disposing pairs of cylinders in an inverted V-bank for reasons of efficiency.

Still further objects and advantages are inherent in my invention and how those as well as the objects hereinabove specifically enumerated are accomplished will become apparent to those skilled in the art from the following detailed description of a presently preferred embodiment thereof, for which purposes I shall refer to the accompanying drawings, in which:

Fig. 1 is a longitudinal sectional view with some parts shown in elevation;

Fig. 2 is a section on line 2—2 of Fig. 1;

Fig. 3 is a medial section showing a variational form of my invention;

Fig. 4 is a fragmentary view showing a variational form of control; and

Fig. 5 is a sectional view showing a further variational form.

Referring now to the drawings, the numeral 5 denotes a horizontally disposed elongated cylinder having a water jacket 6 therearound, the cylinder being suitably mounted atop a crank case composed of upper and lower sections 8; 8a respectively, secured together by bolts 9 extending through flanges 10, the top section 8 being secured to the cylinder block by flange 11 and bolts 12.

Slidably mounted in opposed relationship in the cylinder, I provide pistons 15, 15a to which connecting rods 16 are pivotally connected by

wrist pins 17, the pistons having the usual rings 18.

The crank shaft 20 is journalled at its ends in the crank case and is disposed at right angles to the longitudinal axis of the cylinder. The outer ends of connecting rods 16 are pivotally connected respectively at 22 to the top ends of rock levers 25, 25a, respectively. To the lower ends of the respective rock levers, connecting rods 27 are pivotally connected at 28, said connecting rods being operably connected at their other ends to the cranks 29, 29a on the crank shaft.

The rock levers 25, 25a, respectively, are fulcrumed on eccentric portions 30 of shafts 31, each shaft 31 being journalled at its ends in the crank case and extending parallel to the crank shaft, the journal means being the bosses 41 each presenting a shaft receiving hole 40. To the outer end of each of the shafts 31, I secure a control lever 35 which carries a spring pressed latch 36. This latch has a lower end portion 37 adapted to engage and disengage the recesses 38 in the arcuate locking member 39.

Through the cylinder wall adjacent its left-hand end I provide circumferentially spaced, elongated air inlet ports 45, through which air is admitted to the cylinder. I preferably maintain a constant pressure tending to inject air into the cylinder through these ports, as by use of a blower (not shown) of well-known construction. Ports 45 are elongated so that they are gradually opened and closed by the piston. A fuel injection nozzle 46 of well-known construction communicates with the cylinder midway between its ends, the inlet end of the nozzle being in communication with a fuel source and fuel pump of well-known construction, not shown, the timing of the fuel injection being controlled by conventional cam shaft means, not shown, operatively connected to the crank shaft. Adjacent the opposite end of the cylinder I provide circumferentially spaced exhaust ports 47. While preferably my engine is operated as a Diesel type in which the fuel charge is fired by compression, it is within the purview of my invention to utilize a conventional spark plug for this purpose if desired.

The operation of the engine disclosed in Figs. 50 1 and 2 is as follows: In Fig. 1 the pistons are shown in their outermost position with both the fuel inlet ports 45 and the exhaust ports 47 uncovered. In this position the air under pressure enters through the ports 45 in a direction tangential to the longitudinal axis of the cylinder. 55 As the pistons then begin their next compression stroke the inlet and exhaust ports are covered by the respective pistons and as the pistons near the end of their compression stroke the fuel charge is injected and fired by the compression. By means of the elongated air inlet ports I accom-

plish a gradual opening and closing of the air inlet.

From the foregoing description it will be obvious that by rotation of the shafts 31 by means of the levers 35 the eccentrics 30 are rotated to adjust the fulcrum point of the rock levers and consequently the inward terminus of the compression stroke of the pistons is accordingly varied.

In the device of Fig. 3, I show two cylinders 50 disposed at angles of approximately 45° in a bank in the shape of an inverted V. The crank case is composed of three sections 51, 51a and 51b. The cylinders are water-jacketed at 52 and each has a head 53 ported at 54 for the admission of air under pressure introduced through the intake manifold 55. Each of the ports 54 provides a valve seat 57 against which valve 58 is adapted to seat. Each valve stem 60 passes outwardly through the manifold 55 and carries a disc 63 at its outer end. Between the disc and the manifold 55 a coil spring 65 is interposed to normally urge the valve 58 against its seat. The valve stems 60 are pressed inwardly to move the valves 58 off their seats by the crossed rocker arms 67 which are pivoted on spindle 68 and are alternately actuated by the cam 70 secured on the cam shaft 71. Cam shaft 71 is rotated by means of a wheel 72 driven by a chain belt 76 from a wheel 73 secured on the crank shaft 74. The usual fuel injection nozzles 61 communicate with the inner ends of the cylinders, their inlet ends being in communication with the usual fuel source pump, not shown, controlled by a timing mechanism including conventional cams and cam shaft operatively connected to the crank shaft.

Circumferentially spaced exhaust ports 76 are provided through each cylinder wall at a point spraced inwardly from the inner end of the piston 77 when the piston is in its outermost position. Each piston 77 is connected to one end of a rock lever 80 by means of a connecting rod 81 pivoted at 82, 83. Lower connecting rods 85 connect the lower ends of the rock levers 80 to the crank 86 on the crank shaft by pivotal connections 87, 88.

Rock levers 80 are pivotally mounted on the eccentric portions 90 of shafts 91 in the same manner as described in connection with the device of Figs. 1 and 2, with the exception of the fact that the bearing 94 for each eccentric portion 90 is provided through the rock lever at a point closer to the lower end of the rock lever than to the top end, so as to provide a relatively longer piston stroke and a relatively shorter throw on the crank 88.

While not shown in Fig. 3, it will be understood that I provide a control means for rotating shafts 91 to operate the eccentric portions 90 for the purpose of varying the piston stroke such as described in connection with the device of Figs. 1 and 2.

In Fig. 3, the left-hand piston is shown at the end of its compression stroke and in the firing position, while the right-hand piston is at the end of its power stroke, in which position the air inlet valve 58 has opened to admit air which is preferably injected under pressure as by a blower, the injected air charge forcing products of the previous combustion outwardly through the exhaust ports 76. As the right-hand piston begins its compression stroke from the position shown in Fig. 3, it will first, in conjunction with the oppositely moving air charge, positively com-

plete the scavenging by forcing outwardly through the exhaust ports any products of the previous combustion which might have remained between the inner end of the piston and the exhaust ports. By virtue of the relatively longer stroke afforded by the construction described, the pistons are able to reach an outward movement terminus whereby their inner ends are spaced outwardly from the exhaust ports so that all remaining products of combustion may be positively forced outwardly through the exhaust ports at the beginning of the next inward piston stroke before the compression begins. By the construction described, the valve operating elements are kept lubricated by the oil vapors in the crank case and by disposing the cylinders in an inverted V-bank the valved ends are sufficiently adjacent each other to permit of a simple, efficient and compact valve operating mechanism as shown. As the respective pistons near the end of their compression strokes, a timed injection of fuel is made through the fuel nozzles 61.

As shown in Fig. 4, by interconnecting the fulcrum shafts 30a, which present the eccentric portions as before described, by means of worms 100 on the worm shaft 101 meshing with worm gears 103 on shafts 30a and providing means such as the operating crank 102 for rotating the shaft 101, the shafts 30a may be simultaneously and equally rotated to vary the fulcrum axis of the rock levers.

In Fig. 5, I show a further variational form of engine to which my compression adjustment may be adapted. Here I show a cylinder 110 of a four cycle type of engine, in which a piston 111 is slidably mounted. The piston is operatively connected to crank 115 of the crank shaft 116 by connecting rod 117. The respective ends of the crank shaft are journaled off-center at 118 in a rotatable bearing 119, the latter bearings being journaled in the crank case. A gear 125 is secured to each of the bearings 119, which gears are rotatable to rotate the bearings by means of worms 126 on shafts 127, a shaft 128, which has spiral gears 129 at each of its ends meshing with spiral gears 135 on shafts 127 to simultaneously rotate shafts 127, and a manual operating crank 130. Thus as the operator rotates crank 130 the gears 125 are simultaneously rotated, causing the bearings 119 to move the crank shaft axis towards or away from the cylinder head, thus effecting a compression adjustment.

The broad concept of my invention, as defined by the appended claim, of course may be carried out in structures varying from that herein specifically described, so that the details which I have hereinbefore employed to illustrate an adaptation of my invention are not to be taken as limitative.

I claim:

An internal combustion engine comprising a cylinder, a piston reciprocally mounted in the cylinder, a crank operatively connected to the piston, an exhaust port through the cylinder side wall in position to be alternately covered and uncovered by the piston during reciprocation of the latter, and means for injecting air under pressure into the cylinder while the exhaust port is uncovered, said exhaust port communicating with the cylinder at a point spaced inwardly thereof from the inner end of the piston when the latter is at the end of its outward stroke and being open at all times except when covered by the piston.

DWIGHT W. STABLER.
